UNITED STATES PATENT OFFICE.

LEOPOLD BAKKE, OF CHICAGO, ILLINOIS.

PAPER-GUIDE FOR PRESSES.

1,078,657.

Specification of Letters Patent.

Patented Nov. 18, 1913.

Application filed January 15, 1912, Serial No. 671,284. Renewed September 5, 1913. Serial No. 788,322.

To all whom it may concern:

Be it known that I, LEOPOLD BAKKE, a citizen of the United States, and a resident of Chicago, in the county of Cook and State 5 of Illinois, have invented certain new and useful Improvements in Paper-Guides for Presses, of which the following is a full, clear, and exact specification.

My invention is concerned with stop 10 guides for presses adapted to control the feeding of the paper to be printed to the presses so accurately that the exact registration demanded in two-color and similar work can be readily and easily secured. In 15 devices of this type which have been used prior to my invention, the spring guides which directed the paper to the sheet-stop plates always stood at the same distance above the under guide strips, and this distance must be sufficient to accommodate the 20 thick and heavy paper or bristol board that is sometimes printed. If thin paper was to be printed, the edges, not being held down close to the under guides, might be curved 25 or curled up so that the gripper fingers in swinging down on the edges of the sheets would strike the curled-up edges standing above the proper level and knock the sheet back a little, with the result that the exact 30 registration required for two-color and similar work was not necessarily secured. To obviate this difficulty, by my invention I provide means by which the distance of the spring guides above the under guides at the 35 sheet-stop plates may be accurately regulated and adjusted for any thicknesses of paper, so that no matter how thin the paper, it will not have any space to curl up at the edges and possibly be knocked back out of 40 exact registration by the gripper fingers.

Another feature of my invention is a 45 novel construction whereby I am enabled to produce a stop plate that shall have a vastly greater life than those heretofore used, and to this end, instead of making a stop plate always presenting the same stop surface to the edge of the sheet, I have made one in 50 which four different stop surfaces can be successively presented by means of a simple adjustment.

To illustrate my invention, I annex hereto a sheet of drawings, in which the same reference characters are used to designate identical parts in all the figures, of which,—

55 Figure 1 is a fragmentary view of a por-

tion of a press having my invention applied thereto; Fig. 2 is a view on a larger scale, in section on the line A—A of Fig. 3; through the stop plate and directly associated members of a front guide embodying 60 my invention; Fig. 3 is a transverse section on the line B—B of Fig. 2; Fig. 4 is a similar view in section on the line C—C of Fig. 2; Fig. 5 is a plan view in section on the line D—D of Fig. 2; and Fig. 6 is a top plan 65 view.

In Fig. 1, 10 indicates the framework of a rotary press, of which 11 is the cylinder, 12 is the feed board, and 13 indicates one of the under guides on the surface of said 70 board, with which the front guide shown operates. The supporting sleeves 14, each of which has a supporting rod 15, which is longitudinally adjustable therein by any desired means (such, for instance, as is shown 75 in my Patent No. 1,011,009, dated December 5, 1911) to adjust the position of the stop plates, are secured on the rock shaft 16, which carries the crank arm 17 connected by the link 18 with the customary cam 80 mechanism by which the front guides are thrown up at the proper time to allow the paper to be carried on to the cylinder and down at the proper time to serve as the stop when the sheets are fed into position. 85

The mechanism thus far described may be of any desired construction, and forms no part of my present invention.

The outer end of the supporting arm 15 is rigidly secured in the block 19, which is 90 riveted to the rear of the vertical supporting plate 20 which I preferably employ. This vertical supporting plate 20 is preferably provided with the reduced and turned over upper end 21, which has the slot 22 therein, 95 through which passes the unthreaded portion of the screw 23, which is preferably provided with the milled head 24 by which it is manipulated. A shoulder 25 is provided, together with a collar 26 secured on the body 100 of the screw beneath the end 20 of the supporting plate, so that the screw is free to turn in said plate without having any movement relative thereto other than that of rotation. The two spring guides 27 are of a 105 customary construction, but in my preferred form extend substantially parallel to the under guide 13, a considerable distance in advance of the stop plate with which they are associated, and are preferably connected 110

to the common body portion 28, which is slotted at 29 to embrace the screw, and has the ends 30 adjoining the slot 29 turned down, as shown in Fig. 2, sufficiently so that the screw and the turned down end coöperating with the supporting plate are sufficient to hold the spring guides in position.

While I might, so far as the main object of my invention is concerned, form the stop surface on the supporting plate 20, I preferably employ an entirely distinct and separate stop plate 31, which is preferably composed of some hard or hardened metal, much harder than is desirable to use for the supporting plate 20. This plate 31 is of uniform thickness throughout, and on both its top and bottom edges is provided with a pair of recesses 32 bounded on their outer edges by the projections 33, and separated by the shallower projection 34, so that the projections 33 can coöperate with the edges of the under guides 13 and accurately position the stop plate 31 relative to said under guide. The projection 34, as seen in Figs. 3 and 4, rests on the top of the under guide 13, while the projections 33 extend slightly below and embrace the same. The plate 31 is provided with a couple of apertures through which the screws 35 may be passed and threaded into the supporting plate 20, so that by reversing this stop plate 31, top and bottom, and forward and back, I have no less than four distinct surfaces which may be successively employed, and as the edges of the paper being printed eventually wear the stop surfaces sufficiently so that the adjustment becomes inaccurate, it adds greatly to the life of the guide to provide these four contact surfaces, and, as aforesaid, the plate 31 may be made of much harder material than is convenient to use in the construction of the supporting plate 20.

As I have stated in the opening of the specification, with the construction thus far described, the ends of the spring guides 20, which always press up, would always be at the same distance above the under guides 13. If paper of a thickness substantially equal to the vertical distance between the top of the under guides 13 and the bottom of the spring guides 27 at the stop plate were always employed, this construction would be entirely satisfactory; but where very thin paper is used, it is possible for the edges of the paper to curve or curl up adjacent the spring guides 27 and at the point where the gripper fingers contact with the paper, so that said gripper fingers will knock the paper back. To obviate this difficulty, I employ the adjusting plate 36, which preferably has the turned-over edges 37 embracing the edges of the plates 20 and 31, so as to be guided thereon in its vertical movement. Where the screws 35 are employed, the slots 38 are needed to accommodate the heads of the

screws, and I preferably form the shallow recesses 39 on the under surface to engage the ends of the spring guides and prevent their lateral displacement. At the upper end of this adjusting plate, I form the turned over end 40, through which the screw 23 is threaded, so that by turning the aforesaid screw the adjusting plate may be raised or lowered and the ends of the spring guides 27 be adjusted very near to the upper surface of the under guides 13 for correspondingly thin paper, or adjusted some distance therefrom to permit the use of heavy paper or bristol board. When the plate 36 has been moved to the exact adjustment desired by turning the screw 23, the lock nut 41 is screwed down against the turned-over end 40 so as to lock the parts securely in the desired position of adjustment.

While I have shown and described my invention as embodied specifically in a front guide, it may also be used in side guides, as will be seen from my application No. 673,475, filed January 25, 1912, which I expect to have issued simultaneously herewith.

While I have shown and described my invention in the form which I at present consider best adapted to carry out its purposes, it will be understood that it is capable of modifications, and that I do not desire to be limited in the interpretation of the following claims except as may be necessitated by the state of the prior art.

What I claim as new, and desire to secure by Letters Patent of the United States, is:

1. In a device of the class described, the combination with a sheet-stop plate adapted to be moved into and out of engagement with an under guide or surface, of a spring guide secured at one end relative to said stop plate and having the other end movable relatively thereto to and from the under guide and extending substantially parallel thereto for a considerable distance in advance of the stop plate, and means for adjusting the exact distance the under surface of the spring guide shall be above the upper surface of the under guide at a point directly below the bottom of the stop plate, said means engaging the spring guide at said point.

2. In a device of the class described, the combination with a sheet-stop plate adapted to be moved into and out of engagement with an under guide or surface, of a spring guide secured at one end relative to said stop plate and having the other end movable relatively thereto to and from the under guide and extending substantially parallel thereto for a considerable distance in advance of the stop plate, a member movable to and from the bottom of the stop plate and adapted to engage the upper surface of the spring guide immediately adjacent said bot-

tom, and means for moving said member and securing it in any desired position of adjustment.

3. In a device of the class described, the combination with a sheet-stop plate adapted to be moved into and out of engagement with an under guide or surface, of a spring guide secured at one end relative to said stop plate and having the other end movable relatively thereto to and from the under guide, a member carried by the stop plate and guided thereon and movable to and from the bottom of the stop plate, and adapted to engage the upper surface of the spring guide adjacent said bottom, and means for moving said member and securing it in any desired position of adjustment.

4. In a device of the class described, the combination with a stop-plate member having an apertured offset upper end, of a parallel adjusting plate adapted to slide vertically thereon and having an offset end, a screw journaled to turn in the apertured offset end, and threaded through the offset end of the adjusting plate, and a spring guide secured at one end relative to the stop-plate member and having the other end movable relatively thereto to and from the under guide and engaged by the bottom of the adjusting-plate member.

5. In a device of the class described, the combination with a supporting plate, of a stop plate carried thereby, said plates adapted to be moved to bring the under side of the stop plate into and out of engagement with an under guide or surface, of a spring guide secured at one end relative to the supporting plate and having the other end movable relatively thereto to and from the under guide, an adjusting plate sliding on the stop plate, a screw journaled in the supporting plate and threaded through the adjusting plate, and means for locking the screw in any desired position of adjustment.

45 6. In a device of the class described, the

combination with a supporting plate, of U-shaped spring guides secured to the top thereof at one end and passing beneath the bottom thereof at the other end, a stop plate having a plurality of edges recessed to co-operate with said spring guide, and means for detachably securing said stop plate on the supporting plate with any desired one of the plurality of edges co-operating with the spring guide.

5. In a device of the class described, the combination with a supporting plate, of U-shaped spring guides secured to the top thereof at one end and passing beneath the bottom thereof at the other end, a stop plate of the same design on both faces and having a plurality of edges recessed to co-operate with said spring guides, and means for detachably securing said stop plate on the supporting plate with either face outward and with any desired one of the plurality of edges co-operating with the spring guides.

6. In a device of the class described, the combination with a supporting plate, of U-shaped spring guides secured to the top thereof at one end and passing beneath the bottom thereof at the other end, a stop plate having a plurality of edges recessed to co-operate with said spring guides, means for detachably securing said stop plate on the supporting plate with any desired one of the plurality of edges co-operating with the spring guides, an adjusting plate having overhanging edges embracing the supporting and stop plates, and means for vertically moving said adjusting plate, for the purpose described, and securing it in any desired position of adjustment.

In witness whereof, I have hereunto set my hand and affixed my seal, this tenth day of January A. D. 1912.
